FLEXIBLE MANDREL

George M. Eaton, Ben Avon, Pa., assignor to
Spang, Chalfant & Co., Inc., Pittsburgh, Pa.,
a corporation of Pennsylvania

Application March 21, 1931. Serial No. 524,335

7 Claims. (Cl. 10—107)

My invention relates to the supporting of tubing against deflection or distortion when subjected to exteriorly applied forces, and is particularly applicable to the holding of tubing during the cutting 5 of threads on its surface, or while performing other heavy cutting operations on it.

Much time and effort have been expended in attempting to cut threads on the exterior of pipe by a hobbing operation, in which, and in certain 10 other thread cutting processes, very heavy cuts are taken at one side only of the pipe. In practice it has been found that the pressure exerted by the cutting tool against the pipe in taking such cuts is sufficient to deflect or distort the pipe to 15 such extent that when the cutting operation is completed and the pipe returns to its relaxed shape the threads are so distorted and inaccurate that the pipe cannot be used.

An attempt has been made to overcome this 20 difficulty by inserting a solid cylindrical mandrel in the pipe to support it during the hobbing operation. However, inasmuch as the inner surface of commercial pipe and similar tubular members are ordinarily not accurately cylindrical, a cylindrical mandrel causes the pipe to be deflected out 25 of its normal relaxed shape when it is inserted. Hence, after threads have been cut on the surface of the deflected pipe and the mandrel removed, the pipe returns to its original relaxed shape, thus 30 destroying the accuracy of the threads.

Mandrels having independent supporting elements actuated by fluid pressure or similar means have been tried, but have also been found to be inadequate to support the pipe in its relaxed shape. 35 Just as in the case of solid cylindrical mandrels, fluid pressure mandrels tend to force the pipe to cylindrical shape, or to permit it to be deflected towards cylindrical shape when acted upon by external force. This is in accordance with the 40 well known principle that tubular objects tend to assume cylindrical shape when subjected to internal fluid pressure. For example, if the tube to be supported by a fluid pressure operated mandrel is somewhat elliptical in shape, the mandrel 45 tends to distort it to cylindrical shape. Or, if the mandrel is not sufficiently powerful to do so, a heavy external force applied along the major axis of the ellipse will distort the tube to a shape more nearly cylindrical. In so changing shape 50 the cross sectional area of the tube is increased and the volume of the space occupied by the fluid is correspondingly increased. This occurs both in cases in which the fluid is applied directly to the tube and in cases a mandrel having fluid actuated 55 supporting member is utilized. If the operating

fluid is confined by non-resilient means, such increase in volume reduces the working pressure in the mandrel and permits further distortion of the tube.

It is an object of this invention to provide a 60 method of accurately cutting threads on pipe wherein the pipe is held firmly and rigidly in its normal relaxed shape during the thread cutting operation.

Another object of my invention is to provide 65 a mandrel for supporting a tubular body that conforms accurately to the interior shape of the tubular body and that holds it rigidly in its normal relaxed position.

A further object is to provide an expandible 70 mandrel that is economical to manufacture and that is rugged and easily manipulated.

In accordance with my invention, I provide a mandrel having a plurality of work-engaging members, each member being provided with two 75 independent contact areas. Means are provided for moving the members to bring all of the contact areas into engagement with the inner surface of the tubular body to be supported. The means for moving the supporting members include a 80 wedge member disposed to exert equal forces on the supporting members, and to set up frictional forces between the members and the tubular body, and between itself and the members to lock them in position. 85

The foregoing and other objects of the invention will become more fully apparent as a better understanding of the invention is had upon studying the specific structures described in this specification and shown in the accompanying drawings, in which Fig. 1 is a view in end elevation of an expandible mandrel, embodying my invention, disposed within a tube; Fig. 2 is a view in section of the mandrel shown in Fig. 1 taken on the plane indicated by the line II—II therein; 90 Fig. 3 is a plan view showing in conventional manner a thread hobbing machine in which is mounted a pipe supported by the mandrel embodying my invention; Fig. 4 is a view showing one element of my flexible mandrel disposed within a 100 tube; Fig. 5 is a view similar to Fig. 4 showing means for adapting the mandrel to tubes of various diameters; Fig. 6 is a view similar to Fig. 4 showing, on a reduced scale, a modification of my invention; Fig. 7 is a view in section similar to 105 Fig. 2 of another modification of my invention; and Fig. 8 is a view, similar to Fig. 7, of the modification of my invention shown in Fig. 6 taken on the plane represented by the line VIII—VIII.

The thread hobbing machine shown in Fig. 110

3 is of well known type with which my flexible mandrel is ordinarily utilized. In general the hobbing machine comprises a base 1 upon which is rotatably mounted a hollow head stock or chuck 2 having clutch jaws for receiving a tubular body such as a pipe 3 on the end of which threads are to be cut. A hob 4 for cutting the threads is rotatably mounted adjacent to the end of the pipe 3 on a carriage 5 disposed to be moved longitudinally of the base 1 along guideways 6. The hob 4 may be rotated by any suitable means such as a motor 7 mounted on the carriage 5 and connected to the hob by a transmission mechanism 8. During the cutting operation the carriage 5 is moved longitudinally of the base 1, at proper speed to form threads of the desired pitch on the rotating pipe 3, by means of a lead screw 9 driven in synchronism with the pipe by a gear train 10 that connects it directly to the rotating head stock 2.

20 To insure that the force exerted by the hob 4 in performing the cutting operation will not distort the pipe 3, the end of the pipe is reenforced, in accordance with my invention, by an expandable mandrel 15 disposed within the pipe and held in engagement with it in such manner that the pipe is firmly and rigidly supported in its normal relaxed position. The mandrel 15 ordinarily may be placed in position manually and operated to engage the interior of the pipe 3 by suitable operating mechanism actuated by a T-handle 16. The pipe 3 is shown in the drawings as being of truly circular cross section for simplicity of illustration, but it will be understood that commercially accepted pipe is not made truly cylindrical but varies from such shape to an appreciable extent.

30 For a better understanding of the construction of the mandrel 15 that is adapted to support the pipe in its natural shape, reference may be had to Fig. 4 in which one supporting element 17 only is shown in its retracted position within a tubular object 3. As shown, the supporting element 17 comprises a plurality of rigid members 18, each of which is provided with two contact areas 19 for engaging the inner surface of the tube 3. The rigid members 18, of which three are utilized in this specific structure, are yieldingly held in uniform angular spaced relation in a common plane 40 by connecting spring members 21. In the structure shown, the resilient members 21 are integral with the rigid members 18, the entire element 17 having been cut from a single plate of suitable metal by a cutting torch or other cutting device. To expand the supporting element 17 and move the contact areas 19 into engagement with the inner surface of the tube 3, I provide a conical wedge member 22 that engages a seat 23 at the inner edge of each rigid member 18.

50 If we assume that the element 17 is initially out of contact with the pipe 3 as shown in Fig. 4, it may be readily appreciated that when the conical member 22 is advanced axially between the seats 23 of the rigid members 18 it causes them to move outwardly until one contact area 19 of one member 18 engages the inner surface of the pipe. Inasmuch as there is no resistance to movement of the other two members 18 they will continue to move outwardly until at least one contact area of each has also engaged the pipe 3. Upon further axial movement of the cone 22 the rigid members 18 will pivot about their initial points of contact with the pipe 3 and will slide on the interior of the pipe and on the exterior of the cone 22 until a position is reached in which both of the contact

areas 19 on each of the members 18 engage the pipe 3.

60 In bringing the supporting element 17 into engagement with the interior of the pipe 3 at all six of the contact areas only sufficient force need be exerted to overcome the tension in the springs 21, which is small, and to overcome the slight friction between the various members. As long as one or more of the contact areas 19 has not yet engaged the tubular object 3, the forces within the device are negligible, inasmuch as the members not in full engagement with the pipe are free to move without substantial resistance until they do engage the pipe at both contact areas.

70 However, as soon as all of the contact areas have engaged the pipe 3, further movement of the cone 22 will set up substantial radial forces within the supporting element 17 that will oppose external radial forces that may be applied to the pipe during thread cutting or other machining operations and will set up frictional resistance to oppose change of shape of the element.

80 In the preferred practical embodiment of my invention, shown in Figs. 1 and 2, I utilize two supporting elements 17 and 27 disposed in parallel transverse planes of the tube 3 to be supported. As thus constructed the mandrel 15 may be placed in retracted position within the tube 3, as shown in Fig. 2, and will stand in stable manner while being manipulated to expand it into engagement with the tube. To distribute the forces exerted by the elements 17 and 27 about the tube 3, the contact areas of the two elements are disposed in radial planes at angles of 30° to each other in such manner that twelve substantially equally spaced contact areas are provided. The angular relation between the elements 17 and 27 is maintained by a pin 28 securely held in the plate 27 by a nut 29 and extending through a hole 30 in the plate 17. To permit limited relative motion between the plates 17 and 27, the hole 30 is made somewhat larger than the pin 28 to provide adequate clearance space.

90 The flexible element 27 may be actuated by a cone 32 similar to the cone 22 in the element 17 but extending into the element 27 in the opposite direction. As shown in Fig. 2, the elements 17 and 27 may be expanded simultaneously by moving the cones 22 and 32 toward each other. This may be conveniently accomplished by an operating shaft 34 provided with left and right hand threaded portions which cooperate with complementary internal threads in the cones 22 and 32, respectively. The shaft 34 is connected to the operating handle 16 by means of which it may be rotated to move the cones 22 and 32 toward or away from each other.

100 To hold the elements 17 and 27 in spaced relation, the members 18 of each are provided on their adjacent faces with spacing members 35 that bear against each other. At the other sides of the members 18 there are provided similar members 36 which serve to thicken the elements and provide relatively wide tapered faces 23 and 33 for engaging the cones 22 and 32, respectively.

110 To prevent the cones from turning with the operating shaft 34, keyways 37 and 47 are provided in the seats 23 and 33 of the elements for cooperating with keys 38 and 48 on the cones 22 and 32, respectively. The key 48 and the keyway 47 are fitted in such manner that they closely engage each other but permit normal sliding action. However, in order to permit some relative angular motion between the elements 17 and 27, the keyway 37 is made somewhat larger than 120

the key 38 in the same manner and for the same purpose that the hole 30 is made larger than the pin 28.

In operation the mandrel 15 is placed within the tube 3 and the handle 16 is actuated to turn the shaft 34 in the clockwise direction, as viewed from the right end of Fig. 2. This causes the cones 22 and 32 to approach each other and to force the rigid members 18 of the elements 17 and 27 outwardly. Comparatively small forces will be required to turn the shaft 34 at first and the rigid members 18 will shift about slightly as they move outwardly until all of the twelve contact areas 19 engage the inner surface of the tube 3. After the mandrel 15 has thus adjusted itself to conform to the interior configuration of the tube 3, further rotation of the shaft 34 will build up forces that act radially outward upon the tube 3 through all of the contact areas 19 to support it in its normal or relaxed position. To effectively support the pipe 3 against distortion, the cones 22 and 32 are advanced to such position that the forces exerted upon the tube 3 by the members 18 are as large as can safely be applied without unduly expanding the tube. Inasmuch as the forces exerted by the cones 22 and 32 upon the rigid members 18 are substantially equal, the forces applied to the tube 3 by the contact areas 19 are also substantially equal to each other regardless of the configuration of the interior of the tube 3. Further, during the time that the supporting forces are being built up there is practically no relative motion between the various parts of the mandrel, and, as the radial forces increase, tangential frictional resistances are set up tending to lock the elements 17 and 27 securely in position.

As a result of the radial forces between the contact areas 19 and the tube, frictional resistances are established therebetween which oppose relative circumferential motion of the tube and the supporting elements 17 and 27. Relative motion between the elements 17 and 27 also is opposed by frictional resistance between the spacing members 35 which results from the opposing longitudinal force exerted by the cones 22 and 32. To assist in locking the mandrel, the surfaces of the cones 22 and 32 are disposed at such angles to their axes as to provide for irreversible action between the cones and the seats of the members 18. Hence, after the cones have been moved within the elements to points in which the desired forces are set up, they are held from retracting by the frictional forces between them and the seats 23 and 33. Likewise frictional resistances to motion are set up between the threads in the cones 22 and 32, and the threads of the shaft 34.

It is apparent that after the mandrel 15 has been expanded to apply the required supporting forces to the tube 3, the frictional resistances to motion that are set up between its various parts and between it and the tube 3 are of such nature as to prevent relative motion between the elements of the device when the tube is subjected to externally applied forces. In order to change the shape of the mandrel thus locked it would be necessary to rock or rotate one or more of the rigid members 18 relative to the other members. Such relative rotation of the members would result in relative sliding motion between the members and the cones or the pipe. But as has been explained, such relative sliding motion is effectively resisted by the large frictional forces set up

between the members and the various surfaces which they engage.

After the mandrel has been expanded to its final position and locked by frictional resistance, it functions substantially as would a solid mandrel that had been carefully fitted to conform to the irregularities of the interiors of the pipe. However, inasmuch as the mandrel engages the interior of the pipe at twelve separate and distinct positions, there is a slight tendency to deflect the pipe from its relaxed shape towards a shape in the nature of a polygon having twelve sides. That is, the pipe is deflected outwardly, to a slight extent, at each of the points to which pressure is applied by the twelve contact areas of the mandrel. This deflection is so slight, however, that it has no appreciable effect upon the accuracy of the threads cut on the pipe while thus supported. In view of the negligible effect of this slight distortion it may be said that, for all practical purposes, the pipe is firmly and rigidly supported in its relaxed shape by the mandrel embodying my invention. In using this statement throughout this specification it is to be understood that I am aware of this slight distortion, but neglect it as having no detrimental effect upon the object of my invention, which is to provide a mandrel for supporting pipe against the distorting effect of heavy forces applied to its exterior while cutting threads on it.

With the mandrel thus locked in position within the tube the exterior of the tube may be threaded or otherwise worked upon without danger of springing or deflecting it and impairing the accuracy of the work. After the threading or other operation has been performed the mandrel 15 may be retracted for withdrawal from the tube by turning the operating handle 16 counter-clockwise, which operation causes the cones 22 and 32 to move away from each other. As the cones are separated the working forces within the mandrel 15 are gradually reduced to zero and as the retracting operation progresses the rigid members 18 are drawn inwardly to their inactive positions by the springs 21. The mandrel may then be withdrawn leaving the pipe in its original shape with accurately cut threads of true pitch diameter on its surface.

To prevent damage to the mandrel 15 in the event that the operating handle 16 is actuated when the mandrel is not in a pipe that it is adapted to support, the cones 22 and 32 are made of such length that they will engage each other at the mid-plane of the mandrel before the elements 17 and 27 can be expanded to stress the springs 21 beyond their elastic limits. Incidentally, the stresses within the spring 21 during normal use of the mandrel are quite low inasmuch as the supporting forces are transmitted directly through the rigid members 18.

In the event that it is desirable to utilize one mandrel for supporting pipes of different internal dimensions, adapters or lugs 39 may be applied to the rigid members 18, as shown in Fig. 5. In this view the lugs 39 are shown attached by bolts 40 to the members 18 at each contact position 19. A set of lugs 39 may be provided for adapting the mandrel 15 to each size of pipe with which it is to be utilized.

Under some conditions it may be desirable to support the pipe at the position in which it is gripped by the clutch jaws of the chuck 2 as well as at the position upon which the cutting tool operates. If such support is provided the clutch jaws may be disposed to engage the pipe near the

portion being worked upon and may be tightened to rigidly grip the pipe without danger of distorting it. Apparatus for accomplishing the result is provided by the modification of my invention shown in Fig. 7. In this modification two complete mandrel structures or units, each similar to that shown in Figs. 1 and 2, are operatively connected to a common operating mechanism. As shown, one mandrel unit 15a is disposed near the end of the pipe 3 to support it against distortion by forces exerted by the cutting tool 4a. To prevent distortion of the pipe by the chuck 2 another mandrel unit 45a is disposed somewhat farther within the pipe 3 at the position engaged by the clutch jaws 2a of the rotating head stock.

The two mandrel units 15a and 45a are spaced or positioned by a hollow compression member or nipple 47a. At the ends of the nipple 47a are operating cones 42a, corresponding to the cone 22 in Fig. 4, for engaging and expanding the rigid members of one element in each of the mandrel units 15a and 45a, respectively. Cooperating with the cones 42a in operating the mandrel units are similar cones 52a disposed to expand the other element of each unit. The cones 52a are provided with internal right and left threads, respectively, and are threaded on complementary threads of a relatively long operating shaft 34a that passes through the nipple 47a. As shown, the cones 52a are at the ends of the apparatus and it is apparent that when they are moved toward each other by the shaft 34a they not only operate the particular element which they engage but also force the other elements of the mandrel units on the cones 42a. Consequently, when the shaft 34a is actuated by the handle 16a to tighten the apparatus within the pipe 3 all of the four elements expand until all twenty-four contact areas engage the inner surface of the pipe. As the mandrel elements are forced on the cones 42a the entire apparatus is shortened somewhat and the mandrel units 15a and 45a are moved toward each other. Such motion can readily take place during the adjusting period when there is very little frictional resistance to motion between the contact areas and the pipe. After all the contact areas engage the pipe and pressure is exerted by turning the shaft 34a farther there will be some slight tendency to move the mandrel units toward each other. However, this tendency is readily taken care of by deflection of the resilient elements of the mandrel.

In the event that it is desirable to support the pipe at more than two positions apparatus constructed in accordance with the modification of my invention shown in Figs. 6 and 8 may be utilized. In this modification a plurality of mandrel units 15b, 45b and 55b, respectively, are all mounted on a long operating shaft 34b. At the ends of the shaft 34b the usual right and left threads are provided for engaging complementary threads in end cones 52b. Spacing nipples 47b, having cones 42b at their ends, are provided for separating the mandrel units.

As mandrel apparatus of this type may be made quite long, means are provided for permitting some of the units to move longitudinally of the pipe when the end cones 52b are drawn toward each other. To this end, all of the mandrel units except the one at the end of the pipe are provided with small rollers or wheels 56b mounted at each contact position and disposed in radial longitudinal planes of the pipe 3, as shown in Fig. 6.

From the foregoing description of my tube sup-

porting mandrel and explanation of the manner in which it operates, it is self-evident that I have provided rugged and effective apparatus for firmly supporting a tubular object in its normal or relaxed position to resist distortion from externally applied forces. 80

Although I have shown only a few specific embodiments of my invention and have described them in detail to adequately disclose the invention, it will be apparent to those skilled in the art that many modifications may be made in the details of the mandrels, as in the types of spring elements utilized and in the general configuration and number of the rigid members, without departing from the spirit and scope of my invention as defined in the appended claims. 85 90

I claim:

1. In a mandrel for providing internal support to a tubular object of approximately circular shape in cross section, a plurality of supporting elements disposed in pairs in spaced transverse planes of the object to be supported, each of said elements comprising a plurality of rigid members provided with a plurality of contact areas for engaging the inner surface of the 100 tubular object, a cone disposed to actuate the rigid members of each supporting element outwardly, the cones for actuating each pair of elements being disposed to move toward each other, rigid means disposed to space the elements of 105 each pair, compression members disposed between the cones at adjacent sides of successive pairs to space the pairs, and means for actuating the cones at the ends of the mandrel to move them toward each other and in so doing move the 110 cones in each pair toward each other for expanding equally all of the elements of the mandrel. 115

2. In a mandrel for providing internal support to a tubular object of approximately circular shape in cross section, a plurality of supporting elements arranged in pairs and comprising a plurality of rigid members provided with rollers disposed in radial transverse planes of the tubular object for engaging the inner surface thereof, a cone disposed to actuate the rigid 120 members of each supporting element outwardly, the cones for actuating each pair of elements being disposed to move toward each other, rigid means disposed to space the elements of each 125 pair, compression members disposed between the cones at adjacent sides of successive pairs to space the pairs, and means for actuating the cones at the ends of the mandrel to move them toward each other and in so doing move the 130 cones in each pair toward each other for expanding equally all of the elements of the mandrel. 135

3. Means for radially supporting a hollow work-piece, comprising a plurality of engaging members arranged in a circle and mounted for radial movement and for tilting movement substantially in the plane of the circle, each of said members having two independent contact areas spaced apart from each other, and means for exerting substantially radial pressure upon said members in a direction towards said work-piece, whereby each of said members is caused to seat with both of its surfaces against said work-piece. 140

4. Means for radially supporting a hollow 145 work-piece, comprising a plurality of engaging members arranged in a circle and mounted for radial movement and for tilting movement substantially in the plane of the circle, each of said members having two independent contact areas 150

- spaced apart from each other, an axially movable wedge member contacting said engaging members for moving them in a substantially radial direction, whereby each of said members is caused to seat with both of its surfaces against said work-piece.
5. A mandrel for interiorly supporting a hollow work-piece, comprising a flat plate having portions thereof removed to produce a group of members arranged in a circle and having outer portions for engaging the interior of the work-piece and inner pressure-receiving portions and integral resilient members connecting the first-named members with one another to permit movement thereof substantially in the plane of their circle, and means for exerting substantially radial pressure upon the inner portions of said first-named members.
6. A mandrel for interiorly supporting a hollow work-piece, comprising a plate having portions thereof removed to produce a group of substantially triangular engaging portions arranged in a circle with their bases disposed circumferentially of the circle, each of said bases having two independent contact areas spaced apart from each other, and their apexes directed toward the center of the circle and integral resilient portions connecting said engaging portions, and means for exerting substantially radial pressure upon the apexes of said engaging portions.
7. A mandrel for interiorly supporting a hollow work-piece, comprising a plate having portions thereof removed to produce a group of substantially triangular engaging portions arranged in a circle with their bases disposed circumferentially of the circle, each of said bases having two independent contact areas spaced apart from each other, the sides of said triangles being concave to produce spaces between said portions and the apexes of said portions being directed toward the center of the circle, and U-shaped integral resilient portions disposed in said spaces and connecting said engaging portions, and means for exerting substantially radial pressure upon the apexes of said engaging portions.
